UNITED STATES PATENT OFFICE

ISAAC A. BAUM, OF CHICAGO, ILLINOIS

DOOR SILENCER

Application filed December 3, 1928. Serial No. 323,363.

My invention relates to building construction, and particularly to a new and novel door stop as applied to door frames.

With the gradual increase in the use by the 5 trade of metal frames for openings, the use of metal doors has likewise increased.

However, it has been found that a metal door closing upon an outstanding metal door stop will produce considerable noise and will, 10 in time, become very annoying to those occupied in close proximity to the door.

A number of expedients have been devised to overcome this objection to the use of metal door frames, all more or less efficient for the 15 purpose intended.

An object of my invention is to provide a metal door frame having a resilient block, or a plurality of resilient blocks, in the door contacting face of the door stop to absorb 20 the force of the blow against the stop.

A further object of my invention is to provide resilient blocks that may be adjusted relative to the projection beyond the face of the stop so as to insure a satisfactory result 25 regardless of the amount of wear upon the block.

My invention will be more readily understood by reference to the accompanying drawings, in which.

30 Fig. 1 is a perspective view of a door opening showing the door frame of my construction;

Fig. 2 is a horizontal sectional view, slightly enlarged, showing the device of my construction and invention;

Fig. 3 is a vertical sectional view of the door stop, and

Fig. 4 is a horizontal sectional view showing the door stop before the screw is inserted.

40 By reference to the accompanying drawings, it will be seen that I have shown a wall A, and mortar B with the metal door frame 10, having the anchors 11 and plaster defining and terminal portion 12, the specific details of which have been disclosed in prior copending applications.

The face of the frame 10 is formed into the door stop 13, extending the length of the frame member 10. At a suitable point on 50 the door contacting face of the stop I provide

a pocket for the reception of the resilient block 14. The pocket may be formed in any suitable manner, but preferably as shown, by bending inwardly the ears 15—16 of the door contacting face of the stop 13. A U-shaped band 17 is utilized within the stop to join the two ears 15—16 and thus provide a pocket for the block 14.

The block 14 placed within the pocket is of any suitable shape, preferably the shape of the aperture in the door stop, and is provided with an opening which extends through the length thereof. Before the block 14 is inserted within the pocket provided therefor, an expansion bolt 18 is forced 45 therein, together with the screw 19 for the expansion thereof.

The initial position of the resilient block 14 is shown best in Fig. 4 where the block is simply inserted within the pocket and is not anchored therein. Figs. 2 and 3 show the block with the expansion bolt 18 in an expanded position, thus forcing the block against the walls 16—17 of the pocket.

It is evident that the block 14 will be firmly 75 anchored within the pocket after only a few turns of the screw 19 on the expansion bolt 18. But a further object of my invention is to provide this means for forcing a portion 80 of the block out of the pocket as desired. Additional expansion of the bolt 18 will cause the material composing the block to flow where it will project beyond the face of the stop. Thus adjustment can readily be 85 made by a few turns of the screw 19 when the top of the block wears off in use.

It is obvious that various modifications and variations may be made in the construction herein disclosed, within the skill of the mechanic, and I do not wish to be limited except 90 as indicated in the appended claims.

I claim:

1. In metal door frame construction, the combination of a metal jamb and door stop formed on the face thereof, means integral 95 with said stop forming a pocket in the door-contacting face of said stop, a resilient block disposed within said pocket, a portion of which projects beyond the face of said stop, means for effecting the expansion of said 100

block in said pocket for anchoring said block within said pocket.

2. In metal door frame construction, the combination of a metal jamb and door stop formed on the face thereof, means integral with said stop forming a pocket in the door contacting face of said stop, a resilient block disposed within said block, a portion of which projects beyond the face of said stop, and means within said block, comprising a threaded bolt and an expansion socket for securing said block within said pocket and for permitting adjustment of said block relative to the amount of projection thereof.

15 3. In testimony whereof I have affixed my signature.

ISAAC A. BAUM.
